UNITED STATES PATENT OFFICE.

ANTOINE LACROIX, JR., OF BROOKLYN, NEW YORK.

DESIGN FOR THE EXTERIOR OF A COUNTRY HOUSE.

SPECIFICATION forming part of Design No. 19,207, dated July 16, 1889.

Application filed June 8, 1889. Serial No. 313,610. Term of patent 7 years.

To all whom it may concern:

Be it known that I, ANTOINE LACROIX, Jr., of the city of Brooklyn, in the county of Kings and State of New York, have invented and produced a new and original Design for the Exterior of a Country House, of which the following is a specification, reference being had to the accompanying drawings, forming a part thereof.

- 10 Figure 1 represents a perspective view of a country house showing my design. Fig. 2 represents a horizontal section or plan of the first story. Fig. 3 represents a horizontal section or plan of the second story.
- 15 Similar letters of reference designate corresponding parts in all the figures.

A house of this design consists of two stories with an attic third story within a gable roof, the first story having an octagonal bay 20 in front, the first and second stories having an octagonal bay at one side and a rectangular bay on the other side, the first story having a piazza with a shed-roof, and a part of said story being recessed back of the flat 25 front of the second story, the second story having on a part of its width a front balcony with a gable roof, and the first story having a rear extension the walls of which extend to the level of the floor of the second story, 30 and the gable roof of which extends upward a portion of the height of the main gable, all as hereinafter more particularly described in detail with reference to the drawings.

A B C designate the front of the house, in 35 which the first and second stories are of the same width. The first story has a bay *a*, (see Figs. 1 and 2,) the plan of which is three sides of an octagon. The second story has a flat front, as shown at *b* in Fig. 3, the extreme projection of the said bay being beyond the line of the front of the second story, 40 and the other portion *C* of the front of the first story being recessed back of the flat front of the second story. This configura-

tion may be understood by reference to Fig. 45 1 and a comparison of Figs. 1 and 2. The gable front *C* of the attic story, which is within the peaked roof *d*, is flat and projects very slightly beyond the front *B* of the second story, with consoles *c*. The sides of the 50 first and second stories are flat and flush with each other for a considerable distance from the front toward the rear, where there is a bay *E*, the plan of which presents five sides of a polygon, as shown in Figs. 2 and 3, projecting the whole height of both stories, and over this bay there is a projecting gable *F*, under the sides of which are cantalevers. The first story has a rear extension *G*, the 55 walls of which only extend to the level of the floor of the second story, but the gable roof *H* of which extends to the height of the top of the second story. On the opposite side of the house to this bay *E* and opposite the said bay is a rectangular bay *E'*, which extends 60 the whole height of the first and second stories.

On the front of the first story is a piazza *I*, extending the whole width of the house, with a shed or sloping roof *e*, and in front of the 65 second story for a portion about one-third of the width is a balcony *J* over the balcony first referred to, the said balcony having a gable roof *K*, which extends upward a portion of the height of the main gable *C*. 70 There is also a rear piazza *L* in an angle formed between the bay *E* and the adjacent side of the extension *G*, and this piazza is included within the gable roof *H* of the said extension *G*.

80 What I claim is—

The design for the exterior of a country house, substantially as herein shown and described.

ANTOINE LACROIX, JR.
